UNITED STATES PATENT OFFICE

135,260

DESIGN FOR A COMBINED AIRPLANE BODY AND PROPELLERS

John Robinson, Los Angeles, Calif.

Application May 2, 1941, Serial No. 100,743

Term of patent 7 years

To all whom it may concern:

Be it known that I, John Robinson, a citizen of the United States of America, residing at Los Angeles, in the county of Los Angeles and State of California, have invented a new, original, and ornamental Design for a Combined Airplane Body and Propellers, of which the following is a specification, reference being had to the accompanying drawing, forming part thereof.

Fig. 1 is a plan view of a combined airplane body and propellers, showing my new design.

Fig. 2 is a side elevational view thereof. Both sides of the airplane are substantially identical in appearance.

I claim:

The ornamental design for a combined airplane body and propellers, as shown and described.

JOHN ROBINSON.
